I. V. EDGERTON

SLEEPING BERTH FOR POULTRY CARS

Filed Sept. 26, 1925

UNITED STATES PATENT OFFICE.

ISRAEL V. EDGEERTON, OF CHICAGO, ILLINOIS, ASSIGNOR TO PALACE POULTRY CAR COMPANY, OF CHICAGO, ILLINOIS, A CORPORATION OF ILLINOIS.

SLEEPING BERTH FOR POULTRY CARS.

Application filed September 26, 1925. Serial No. 58,753.

The present invention has for its object to provide an improved sleeping berth more especially adapted for use in connection with railway cars for the transportation of live poultry. An example of this type of poultry car is shown in Patent No. 1,512,215 granted to me October 21, 1924.

In shipping live poultry in cars of the character above mentioned, it is customary for an attendant to remain in the car with the poultry until it arrives at its destination. The present invention contemplates the provision of a sleeping berth for the attendant, the construction of this berth being such that when not in use, it may be readily elevated to a position near the top of the car, where it will not interfere with the free passage of the attendant through the central compartment of the car.

The invention consists in the features of novelty hereinafter described, illustrated in the accompanying drawing, and particularly pointed out in the claims at the end of this specification.

Inasmuch as the present invention is applicable to cars of the type shown in the above mentioned Patent No. 1,512,215, in which the body of the car is provided with a central compartment for occupancy of the attendant, storage of feed, etc., I have not deemed it necessary to illustrate the general construction of the car, as it will be readily understood how my invention will be applied thereto.

Figure 1 is a view in side elevation showing a vertically movable sleeping berth with means whereby it may be held in raised or lowered position. Figure 2 is a view in horizontal section on line 2-2 of Fig. 1, showing one end of the berth. Figure 3 is an end view showing the opposite end of the berth from that illustrated in Fig. 2.

In the drawings, A and A' designate metal bars that will extend beneath and be secured to the top portion A² of the car. These bars A and A' (which may be Z-shaped in cross section) are shown as formed with flanges a and a', the upper flanges a serving to enable the parts to be bolted to the upper portion of the car, while the bottom flanges a' form means for attachment thereto of the parts to be suspended therefrom. Vertical posts or bars B are arranged adjacent the side wall A³ of the car and have their up-

per ends connected to a cross bar C that extends between the bars A and A', while the lower ends of the bars B are suitably connected to the base plate D (see Fig. 2) that will be bolted to the floor of the car. Between a cross bar D' that is bolted to the vertical posts B and the angle bar C at the top of the posts B, extend the vertical guide bars E. Around the guide bars E passes a guide F that may consist of a U-shaped bar having outwardly bent ends riveted to the upstanding flange of an angle bar G that forms one of the ends of a berth or bed frame. At the opposite end of this berth or bed frame is a similar angle bar G' and between the angle bars G and G' extend a spring bed bottom that may consist of metal strips H connected to the bars G and G' by coil springs h. To the upstanding flanges of the end bars or angle bars G are attached corner irons or castings J that support the side rails K of the berth or bed frame. The castings J at one end of the bed frame are shown as formed with openings j adapted to receive chains L whereby one end of the bed frame will be supported. The upper ends of the chains L will be connected to hooks M attached to the bars A and A' and the lower ends of the chains L will be furnished with hooks N whereby the end of the bed may be adjusted to any desired height.

The bar D' that extends between the vertical posts or bars B forms a support whereon the guide F may rest when the bed frame is in lowered position for use. Through the bar C is passed one end of a suspension hook or bracket R, this hook being pivoted in such manner that it may be turned to engage the guide F when the frame is to be held in elevated position, or may be turned to one side and disengaged from the guide F when the bed frame is to be lowered. Above the opposite end of the bed frame and pivotally connected to one of the bars A or A' is a similar hook S, this hook being adapted to be turned to the position shown in Fig. 1 when the bed frame is to be held in elevated position, and being adapted to be turned a quarter revolution when the bed frame is to be lowered.

The elevated side rails K of the bed frame serve to guard against the danger of the occupant being thrown from the bed by the motion of the car, and the arrangement of

the guide bars E—E and guide loop F serve to give steadiness to the bed frame while the car is in motion.

From the foregoing description it will be seen that when the bed frame is raised to the position indicated by dotted lines in Fig. 1, it will be adjacent the ceiling of the car, where it will not interfere with the free passage of the attendant within the central compartment of the car. The location of the vertical posts B and the bars F adjacent the side wall of the car prevent their occupying the space that will be needed for other purposes.

15 The precise details of construction above set out may be varied without departing from the spirit of the invention and features of the invention may be employed without its adoption as an entirety.

20 What I claim as new and desire to secure by Letters Patent is:—

1. In a poultry car, the combination with a bed frame, of a vertical guide arranged between one of the walls of the compartment 25 of the car and an end of the bed frame, a part on the frame embracing said guide and slidable vertically thereon, a support whereon said end of the frame may rest when in position for use, suspension means for the opposite end of the frame, and means for holding the frame in elevated position when not in use.

2. In a poultry car, the combination with a bed frame, of a vertical guide arranged between one of the walls of the compartment of the car and an end of the bed frame, a part on the frame embracing said guide and slidable vertically thereon, a support whereon said end of the frame may rest when in 30 position for use, vertically adjustable suspension means for the opposite end of the frame, and means for holding the frame in elevated position when not in use.

3. In a poultry car, the combination with a bed frame, of a vertical guide arranged adjacent one of the walls of the compartment of the car, a part on the frame to engage said guide and move vertically thereon, a support whereon said frame may rest 45 when in position for use, suspension means for the opposite end of the frame, and pivoted hooks for holding the frame in elevated position when not in use.

4. In a poultry car, the combination with a bed frame, of vertical guide bars arranged adjacent one of the walls of the compartment of the car, a metal loop on the frame to engage said guide bars and move verti-

cally thereon, a cross bar whereon said frame may rest when in position for use, 60 suspension means for the opposite end of the frame, and means for holding the frame in elevated position when not in use.

5. The combination with a bed frame having at its sides elevated rails, of a vertical guide arranged adjacent one end of said bed frame, a part on the bed frame to engage said guide and move vertically thereon, a support whereby one end of said frame will be sustained when in position for use, suspension means for the opposite end of the frame, and hooks for holding the frame in elevated position when not in use.

6. In a poultry car, the combination with a bed frame, of vertical posts arranged adjacent one of the walls of the compartment of the car, a cross bar extending between said posts at a distance from the top thereof to form a support whereon said frame may rest when in position for use, a guide extending vertically from said cross bar, a part on the frame to engage said guide and move vertically thereon, suspension means for the opposite end of said frame, and means for holding the frame in elevated position when not in use.

7. In combination, a poultry car having a stateroom, flexible members depending from the top of said stateroom, a bed frame suspended at one end on said flexible members, a vertical frame member opposite the other end of said bed frame, interengaging means on said other end and said frame member supporting said other end in lowered position and opposing endwise swaying movement of said bed frame, and means by which said bed frame is supported in elevated position when not in use.

8. The combination with a railroad car, of a berth, means including a flexible element for suspending the berth in its lowered horizontal position for use, said means looped through an end of the berth and terminating in a hook whereby the berth may be adjusted to any desired height, and other means for supporting the berth in an elevated horizontal position when not in use.

9. The combination with a railroad car, of a berth, means including a chain looped through an end of the berth and terminating in a hook whereby the berth may be suspended at any desired height in its lowered horizontal position for use, and other means for supporting the berth in an elevated horizontal position when not in use.

ISRAEL V. EDGERTON.
